OIL STILL

John H. Lawrence, New York, N. Y., assignor to
 Metropolitan Engineering Company, Brooklyn, N. Y., a corporation of New York

Application September 27, 1930, Serial No. 484,776

1 Claim. (Cl. 196—110)

My invention relates to oil stills of the pipe or tube and drum type for the cracking of petroleum hydro-carbon and for the distilling generally of petroleum and similar products.

5 In stills of the above type the oil is heated while passing through a tube or pipe in a furnace and is then passed into a separating or digesting chamber to which little or no additional heat is added. The hydro-carbons to which the heat is 10 imparted are decomposed at high temperatures to a greater or less extent depending on the constitution of the oil, time of heating and other factors and in this decomposition the carbon is set free in quantities depending on the composition 15 of the oil and the extent of cracking. This carbon may act as an insulating material if it should settle on the inner wall of the heating tubes and would thus cause over-heating and destruction or rupture of the tube.

20 Heretofore the heating tubes have not been subjected to any substantial extent to direct contact with, or to the direct radiation of heat from, the furnace but have been heated by contact with, the products of the completed combustion and, 25 therefore, by conduction rather than by radiation.

Objects of my invention are to provide a method of heating oil, in a still, in which the oil is subjected to direct radiation from the burning fuel in the combustion zone; in which the transfer of heat into oil or hydro-carbons is at the highest rate; and in which this heating is accomplished without danger of destruction of the heating tube.

30 35 With these and other objects in view, which will more fully appear from the following description, my invention comprises the method and apparatus described in the following specification.

40 Various features of the invention are illustrated in the accompanying drawings in which:—

Fig. 1 is a perspective view, with portions broken away, of the heating pipes or coils and combustion chamber of an oil still embodying a preferred form of the invention;

Fig. 2 is a cross-sectional elevation of the furnace and heating tubes shown in Fig. 1;

Fig. 3 is a perspective view of a furnace and heating coil similar to that of Fig. 1 embodying 50 a modified form of the invention;

Fig. 4 is a cross-sectional elevation of the furnace and heating tubes of Fig. 3, and

5 Figs. 5 and 6 are, respectively, a longitudinal view and a cross-sectional view of a length of individual tubing or pipe forming an element of the preferred embodiment of the invention.

In my invention the fuel is burnt in the combustion zone and is then drawn through an outlet and then to the exhaust flue or stack. The fuel may be of any suitable or available type, 10 preferably a fluid fuel such as oil, gas or powdered coal. The oil to be heated is first passed into the heating coils in the preheating or outlet flue of the furnace. In these coils in which the oil is subjected to heating by conduction of the 15 heat from the hot combustion gases, the oil is passed in parallel paths through parallel coils to provide a moderate velocity through the coils and to give the oil sufficient time to abstract the maximum amount of heat from the hot combustion 20 gases. This parallel arrangement of the coils also enables the oil to pass through the pre-heating coils with a minimum drop in pressure and to thus preserve the pressure.

The oil streams are then reunited and passed 25 in a single continuous stream through lengths of pipe connected in series to form a continuous coil. The lengths of pipe of this coil line the combustion chamber, or the walls of the combustion chamber, and are subjected to direct radiation 30 from the burning gases at a maximum intensity.

To increase to the greatest extent possible the absorption of heat, the tubes exposed to direct radiation are provided with fins extending between adjacent tubes to receive the heat reaching the spaces between the tubes and conduct this heat into the interior of the tube. The oil then passes from the coil into a receiving drum, digesting chamber or other distilling apparatus.

35 40 During the passage of the oil through the pre-heating coils in which it is heated by conduction of heat from the products of the completed combustion, the velocity of the oil and consequently the drop in pressure are relatively low. The oil then enters a continuous coil, the pipes of which are subjected to direct radiation, at a pressure sufficient to provide the maximum velocity of oil 45 through the pipes heated by radiation and to thus sweep out of this coil the carbon that may 50

be formed by a partial or initial cracking of the hydro-carbon.

Referring more particularly to Figs. 1 and 2 of the accompanying drawings, oil is supplied to an inlet header 10 from which it passes in parallel into a number of heating pipes 11, four such pipes being shown by way of example. These pipes extend transversely through the outlet flue 12 of the furnace and are united at alternately opposite 10 projecting ends to adjacent parallel heating tubes by means of the return bends 13 and 14. Any suitable type of return bend may be employed, right-angled ones with end plugs being preferred, as they permit a ready access to the tubes for 15 cleaning.

The pipes 11 nearest the inlet ends of the flue 12 deliver into the header 15. From the header 15 the oil enters one of a number of pipe or tube lengths 16 that are arranged about the inner 20 surface of the combustion chamber 17. The tubes 16 project through end walls of the combustion chamber 17 and are connected in series by return bends 18 and 19 at the projecting ends. The return bends 18 and 19 may be similar in form and 25 construction to the return bends 13 and 14. A drain 20 may be arranged at the lowermost of the return bends 18 and 19. The oil thus passes in a continuous stream through the pipe lengths 16 at a velocity much greater than that of its 30 passage through the preheating coils 11. In the example shown in Figs. 1 and 2, the velocity through the pipes 16 would be four times that through the preheating pipes 11. From the last 35 of the pipes 16 the oil passes through the outlet pipe 21 to the receiving or separating drum or digesting chamber not shown.

Fuel for combustion in the combustion chamber 17 is supplied through a pair of fluid fuel burners 22 and 23 positioned at opposite ends of 40 the furnace. These burners may be of any suitable type, oil burners being shown by way of example. The air and fuel supplied through these burners is burned in the combustion chamber 17 and the products of combustion after having given up heat by radiation to the pipes 16 45 pass through the outlet flue 12 and impart heat

to the heating pipes 11. They are then withdrawn through an outlet flue 24 and thence through a pair of outlet ducts 25 and 26 to inlets arranged at opposite ends of a fan 27. The fan 27 is driven by a motor 28 and delivers the exhausted products 5 of combustion to a flue or stack 29.

To increase to the maximum extent the radiation receiving capacity of the tubes 16, they are provided with flanges or fins 30 arranged to extend longitudinally from the outer surface of the 10 tubes at positions on diametrically opposite sides thereof as shown in detail in Figs. 5 and 6. These fins are not made continuous with the length of the pipe or tube but are made in short areas in order to prevent distortion. The fins are arranged 15 between successive pipes as shown in Fig. 2 occupying the spaces between adjacent pipe lengths, and thereby intercepting heat rays directed between the pipe lengths and receiving the heat of such radiation and conducting it to the pipe. 20

A suitable insulating material 31 encloses the outer surface of the heating tubes 16 and the outermost tube 11 and prevents loss of heat therefrom. In the modification shown in Figs. 3 and 25 4 the arrangement of the tubes or pipes 11 and 16 and of the combustion chamber 17 and outlet flue is similar to that of Figs. 1 and 2, but the combustion chamber 17 is cylindrical, or circular in cross-section, so that each of the tubes or pipes 30 16 is equidistant from the center of the combustion chamber and thus receives an equal amount of radiated heat.

What I claim is

An oil still comprising a combustion chamber having a wall formed of parallel bare horizontal heat absorbing tubes projecting at their opposite ends beyond said combustion chamber, said tubes having bare fins spanning the space between adjacent tubes to form a substantially continuous furnace wall exposed directly to the heat in said furnace, and burners at opposite ends of said combustion chamber to burn fuel in direct heat transferring relation to said bare tubes, and an off-take for products of combustion midway of 40 said last named ends. 45

JOHN H. LAWRENCE.
